UNITED STATES PATENT OFFICE.

GEORGE W. MULLER, OF WASHINGTON, DISTRICT OF COLUMBIA.

RAIL-JOINT BAR OR FISHPLATE.

Application filed April 30, 1927. Serial No. 187,981.

The present type of rail joint bars or fish plates as they are known in the art and now used as standard equipment by various railroads throughout the country for connecting adjacent rail ends have proven wholly inadequate and inefficient and their defects have resulted in numerous and frequent disastrous railway wrecks.

The defects of the present rail joint bars consist in that they are too short and of improper design and consequently they become loose and allow the rail ends to dip at the joints and batter at the ends of each rail a mound or hump usually forming in the ball of the rail at each end of the bar plate or just beyond the same resulting in the wheel load running down an incline as it approaches the joint and delivering a hammering lick on the rail ends greater than it would be if the rail ends were held level and on a line with the major portion of the length of the rail.

The continued travel of the wheels over the joint causes the ends of the rails to batter, or the top ball part of the rail to batter, some times split, break off, crumble or break, thereby impairing the smooth tread surface of the rail at the travel of the wheels thereover, such low spots in the rail length causing the train to sway and lunge from side to side and the wheel flanges kissing and flapping against the side of the ball of the rail at the joint and the descent of heavy wheel loads falling into these low joint spots sets up a destructive vibration in the track rails and renders the upkeep of the joints extremely expensive.

Railroads at present are forced to expend annually considerable money in the maintenance of present type rail joints owing to the structural defects therein and the damaging consequences above stated. Although various attempts have been made to avoid these consequences as by removing the plates and sawing off the rail ends, building up the ball of the rail by electric and other welding processes, the solution of the problem has not as yet been presented.

A further defect in the present type rail joints consists in that the continual dipping and beating down of the joints forces the ties into the ballast or bed and in many places causes the joints to "pump", that is, allow water to run to the low bed part where the ties are driven down and this condition becomes worse from time to time until it is

necessary to raise the track, clean out the ballast and refill the new ballast to build up the joint, all of which is obviously an added expense in the maintenance of the railway.

Many other defects are present in these known rail joints and in many instances the bar is completely broken by excessive wheel lick hitting them at the joints resulting in derailments and broken wheel flanges or axles or other parts of the locomotive or other rolling stock and in all it is a difficult problem and one which deserves careful attention and the efforts of those skilled in the art to solve.

It is the object of the present invention to provide a rail joint which will effectively overcome all of the objections to those now in use and which will reliably and rigidly maintain the balls of the rails in proper alignment for an unlimited period and minimize so far as possible railway wrecks due to imperfections or damage to the tracks.

A further object of the present invention is to provide a rail joint wherein the bulk of the metal constituting the joint bar is presented at the meeting ends of the rails, fitting under the ball of the rail and so constructed as to direct and distribute the pressure or strain imposed at the joint to the proper point or points of reinforcement.

A further object is the provision of a joint bar of substantially pyramidal or arch shape at the medial portion constructed to hug and snugly fit at all times against the web and underside of the ball of the rail at the point where the rail ends meet and where the metal is mostly needed at the moment of the wheel lick.

The invention has for a further object additional improvements in major and detail features of structure which all tend toward a perfection of rail joint structure calculated to vastly improve and render more efficient this important detail of the equipment of railways.

In the accompanying drawings wherein a plurality of approved embodiments of the invention are illustrated:

Figure 1 is a side elevation of one form of my improved rail joint.

Figure 2 is a horizontal longitudinal sectional view of the joint plate on one side of the rail showing the three point engagement of the joint bar with the web and also with the base flange of the rail.

Figures 3, 4 and 5 are vertical cross sec-

tional views taken on the lines 3—3, 4—4 and 5—5 of Figure 1.

Figures 6 and 7 are vertical cross sectional views taken respectively on the same 5 planes as indicated by lines 3—3 and 5—5 of Figure 1, showing modified forms of the joint bars.

Figure 8 is a side elevation of a slightly different form of joint bar from that shown 10 in Figure 1.

Figures 9, 10, 11 and 12 are vertical cross sections taken on the lines 9—9, 10—10, 11—11 and 12—12 of Figure 8.

Figure 13 is a similar view taken on the 15 same plane as indicated by line 10—10 of Figure 8, showing a modified form of the joint bar shown in Figure 8.

Figure 14 is a detail perspective view of one end of the joint bar shown in Figure 13.

20 Figure 15 is a vertical cross sectional view of the modified form of the bars shown in Figures 13 and 14, taken on the plane indicated by the line 12—12 of Figure 8.

Figure 16 is a view similar to Figure 2, 25 showing one end of a modified form of the joint plate.

According to the arrangement in Figs. 1 to 5 each of the companion joint bars is formed considerably longer than those now 20 in use as observation and experience has taught that the latter are not of sufficient length to withstand the stress and strains to which they are subjected. Accordingly the improved bar is of a length to span and 35 overlie three ties as shown in Fig. 1, the medial portion 50 of each bar being arranged to fit between the ball of the rail and base and being gradually increased in thickness downward toward the rail base for the purpose specified and terminating in depending 40 flanges 51 partially embracing the rail base at its sides. The parts of the bar between the medial rail engaging portion and the terminals of the bar are spaced from the web 45 and from the edge of the base flange of the rail while the terminals of the bar are offset inwardly or constructed to engage and bear against the web of the rail as indicated at 52 in Figures 2 and 5, and against the edge 50 of the base flange of the rail as shown at 52 in Figure 2.

The enlarged medial portion of the bar is 55 preferably placed upon a tie plate 53 while the contiguous bar portions which lie in spaced relation with the rail web are increased in depth as indicated at 54 and ap- 60 pertured at 55 to accommodate bolts which may be used to increase the clamping effect on the rail ends and to improve the efficiency 65 of the joint. The portions of the bar lying outwardly of the depending flanges 54 are appropriately shaped to overlie the adjacent ties while the extreme ends of the plates are again increased in depth and provided with 70 inwardly projecting flanges 56 underlying

the base of the rail and embracing the same as shown in Fig. 5.

The modification illustrated in Figs. 6 and 7 is of a construction similar to that illustrated in Figs. 1 to 5 except that the bar at 70 each side of the rail is provided with an integral flange underlying and extending laterally of the rail base to provide an integral tie plate thus dispensing with the necessity of providing separate tie plates for the joint. 75

According to the embodiment illustrated in Figs. 8 to 12 the joint bar is of such length as to span and overlie four ties in such manner that the laterally prominent medial portion 60 of the bar overlying the joint is 80 located between two adjacent ties and this portion of the bar is provided with a depending flange 61 apertured to accommodate a bolt 62 by which the companion bars are securely bolted together. The flanges 61 85 are provided with an inward extension 64 underlying the rail base and the portion of the bar lying outwardly of the medial portion 60 which is spaced from the rail web as shown in Fig. 11 is provided with depending flanges 65 lying between adjacent ties to add additional strength to the bar and joint. The terminal portions 60 are arranged to bear against the rail web so as to set up a desirable resiliency tending to maintain the 90 nuts on the bolts and also to maintain the medial portion of the bar snugly fitted and positioned under the ball of the rail, this resiliency being set up, as will be understood, by tightening the bolts which pass through 95 that portion of the bar lying in spaced relation with the rail web.

Joint bars of the length herein described are found to be considerably more efficient 100 than those of standard size now in use and although the initial expense due to the additional material required is somewhat greater than formerly, in the end the longer bars prove more economical from the standpoint of maintenance and reduction in wear and 105 tear on railway equipment.

According to the embodiment illustrated in Figs. 8, 10 and 12 the portions of the bar overlying the ties are seated upon tie plates 110 67 but, if preferred, these portions of the bars may be provided with integral extensions 68 as suggested in Figs. 13, 14 and 15 to serve the purpose of tie plates.

Although in the various embodiments of the invention herein described and illustrated each joint is shown as comprising two plates, it will be readily understood that in a number of the embodiments it will be possible to dispense with one of the joint bars and employ only one with the usual attaching 120 bolts for applying the bar directly to the rail only at one side of the latter.

The bars are specially designed in such manner that the portions lying in spaced relation to the web of the rail, when the joint 125

is assembled, exert an exceedingly high pressure against the heads and nuts of the bolts which pass through these portions of the bar and adjacent portions of the rail.

5 What I claim:—

1. A joint bar including an elongated body provided with a reinforced medial portion adapted to snugly fit between the ball and the base of the rail and against the web thereof, and bearing flanges at the terminals of the bar adapted to bear against the rail web.

2. A joint bar comprising an elongated body reinforced at its medial portion to snugly fit against the web and throat of the meeting ends of the rails and on top of the rail flange, the end portions of the bar being spaced from the web of the rail, the outer sides of the terminals of the bar extending downwardly below the flange of the rail and inwardly projecting flanges on said downwardly extending terminals, said flanges engaging the underside of the base of the rail.

3. A joint bar comprising an elongated body, reinforced at its medial portion to snugly fit against the web and throat of the rail ends and on top of the rail flange, the end portions of the bar being spaced from the web of the rail but engaging the web at their terminal portions, said terminal portions also extending downwardly below the flange of the rail, and inwardly projecting flanges on said downwardly extending terminals, said flanges engaging the underside of the base of the rail.

4. A joint bar comprising an elongated body having its central portion thickened and adapted to fit snugly against the full height of the web of the rail, under a portion of the ball of the rail and on top of the rail flange and diminishing in thickness toward its terminals, a portion of the bar between its centre and each end resting on top of the rail flange, the outer edges of said

portion extending downwardly between the ties and clear of the edges of the rail flange, said downwardly extending portions having apertures adapted to receive bolts, said bolts passing beneath the base of the rail.

5. A joint bar comprising an elongated body having a relatively thick central portion, the inner side of said thick portion snugly fitting against the web and the underside of the ball of the rail and on the

flange thereof, the top edge of the bar sloping from said central thick portion toward the ends of the bar and spaced from the under side of the ball of the rail.

6. A rail joint bar having a relatively thick middle portion and having cavities on its back side, whereby said bar bears at three points against the web of the rail.

7. A rail joint bar plate having a relatively thick middle portion and reinforced on its outer side, said reinforcement increasing toward its bottom side, and having cavities on its back side whereby to bear at three places against the web of the rail.

8. A rail joint bar including a body provided with an enlarged medial portion adapted to snugly fit between the ball and base of a rail and against the web thereof, the extremities of the bar being also adapted to bear against the web of the rail, the portions of the bar lying intermediate the medial portion and the extremities being normally spaced from the web, said spaced portions having apertures adapted to receive clamping bolts.

9. A rail joint bar including a body provided with an enlarged medial portion adapted to snugly fit between the ball and base of a rail and against the web thereof, the extremities of the bar being also adapted to bear against the web of the rail, the portions of the bar lying intermediate the medial portion and the extremities being normally spaced from the web, said spaced portions having apertures to receive clamping bolts, and integral flanges formed on the lower edges of the bar and projecting beneath and in engagement with the base of the rail.

10. A rail joint bar having a relatively thick medial portion and downwardly extending flanges on its lower edge, said flanges being adapted to bear at three points against the edge of the base of the rail.

11. A rail joint bar having a relatively thick medial portion and having cavities on its inner side whereby said bar bears at three points against the web of the rail, and downwardly extending flanges on the lower edge of the bar adapted to bear at three points against the edge of the base of the rail.

In testimony whereof I affix my signature.

GEORGE W. MULLER.
